CHARLES G. ERICSON, OF TORONTO, ONTARIO, CANADA

RAIL ANCHOR

Application filed June 24, 1929. Serial No. 373,107.

This invention relates to rail anchors for preventing the longitudinal creeping of rails, and more particularly to rail anchors of the one-piece type adapted to be forced into gripping engagement with the rail.

Resilient or flexible rail anchors of the one-piece type have been extensively used heretofore, and in many of these prior constructions jaws or projections are provided at the opposite ends of the rail anchor to extend over the edges of the rail base flange, but when overhanging jaws are provided at the opposite ends of the rail anchor for engagement with the upper face of the rail base, the rail anchor is more or less difficult to apply to the rail, and it is likely to be subjected to excessive strains during its application to the rail, and which excessive strains continue unvaryingly when the device is in its operating position.

In the one-piece flexible or resilient rail anchor employed heretofore, difficulty has also been experienced in developing a construction which will not move lengthwise of the rail when subjected to a normal or average load thrust but which is capable of gradually increasing its grip on the rail under an exceptionally strong load thrust to relieve the rail anchor from destructive stresses.

The present invention seeks to overcome the above mentioned difficulties and relates to a one-piece rail anchor having a shank adapted to extend transversely of the rail in engagement with the lower face of the rail, and provided at one end with one or more overhanging jaws adapted to firmly grip the upper face of the rail base flange and provided at its opposite end with a laterally extending slightly resilient arm adapted to be forced into firm abutting engagement with an edge of the rail in non-overhanging relation therewith.

A more specific feature of the invention resides in the construction of the laterally extending arm whereby a side face of the arm is positioned to abut against the rail edge and is connected to the shank of the rail anchor by a curved or arcuate portion.

The above and other features of the invention and novel arrangement of parts will be

best understood from the following description when read in connection with the accompanying drawings which illustrate good practical forms thereof.

In the drawings:

Fig. 1 is a perspective view of a rail anchor constructed in accordance with the present invention and shown as secured to a rail in position to abut against a tie;

Fig. 2 is a vertical sectional view through the base of the rail of Fig. 1 and shows the rail anchor of Fig. 1 in gripping engagement with the rail;

Fig. 3 is a top plan view of the parts shown in Fig. 2;

Fig. 4 is a top plan view of a modified type of rail anchor;

Fig. 5 is a top plan view of a further modification of a rail anchor;

Fig. 6 is a top plan view of still a further modified form of rail anchor embodying the features of the present invention; and

Fig. 7 is a side elevation of the jaws of Fig. 4.

The rail anchor of the present invention is shown as applied to a rail of well known construction and consisting of the wheel engaging portion 10 and base 11 which is connected to the wheel engaging portion 10 by the centrally disposed, upstanding web 12, and the base 11 is provided with the usual inclined upper faces 13 and with the vertical edges 14 at the opposite sides of the rail base.

In the various embodiments of the invention illustrated in the drawings the rail anchor is shown as formed entirely of sheet metal, but it will be apparent that the same may be forged or otherwise constructed.

Referring first to the form of the invention illustrated in Figs. 1, 2 and 3, the rail anchor consists of a shank 15 adapted to extend across the under face of the rail and the upper edge 16 of this shank is constructed to rest firmly against the under face of the rail base. The rail anchor, in accordance with the present invention, is provided at one end with one or more overhanging jaws adapted to engage the upper face 13 of the rail base flange, two of these overhanging jaws are

shown in Figs. 1 to 3 inclusive and in Figs. 5 and 6, while three overhanging jaws are shown in the modified construction of Fig. 4.

While the overhanging jaw or jaws just mentioned for holding the upper edge 16 of the shank 15 firmly against the under face of the rail constitutes an essential part of the present rail anchor, as above pointed out the present invention relates more particularly to the construction of the laterally extending slightly resilient arm 17 provided at the opposite end of the shank 15, and adapted to be sprung or forced into abutting engagement with the edge 14 of the rail. It is contemplated that this resilient arm may be given various constructions, some of which are suggested in the different views of the drawings, and the construction of the rail anchor of the present invention is such that when the rail anchor is secured to a rail the shank 15 will extend across the under faces of the rail base at either right angles to the longitudinal axis of the rail, or at a slight inclination to such longitudinal axis in position to cause a face 25 of the shank to abut firmly against the tie 18, as will be apparent from Fig. 3.

The slightly resilient arm 17 in its various constructions extends laterally from the shank 15 in the direction of the on-coming traffic, as will be apparent from Fig. 1 of the drawing, in which the direction of the traffic is indicated by the arrow. The arrangement is such that the pressure of the rail anchor against the tie will tend to slide the portion 35 of the arm 17 abutting against the rail edge 14 lengthwise of the rail in a direction to increase the gripping action of the rail anchor on the rail.

In the embodiment of the invention shown in Figs. 1, 2 and 3 of the drawings, the laterally extending arm 17 is given the construction shown by bending the right-hand end portion of the blank forming the rail anchor laterally of the shank 15 in the form of a loop and by bending the end portion of this arm back upon itself so that the outer side face of the arm 17 is positioned to abut against the rail edge 14, as best shown in Fig. 3. As a result of this construction a relatively wide portion 19 of the arm 17 abuts against the rail edge 14 and this portion of the arm 17 preferably extends upwardly a sufficient distance above the edge 16 of the rail anchor shank to engage practically the entire vertical edge 14 of the rail base, as will be apparent from Fig. 2. This construction is conveniently imparted to the rail anchor by forming an upstanding shoulder 20 on the rail anchor at one end of the rail engaging surface 16, and by cutting or shaping the upper surface of the arm 17 so that it slopes gradually upwardly from the shoulder 20 to the outer end of the arm, as will be apparent from Fig. 2.

The shoulder 20 is preferably so positioned

70 rail, this shoulder will lie in slightly spaced relation to the vertical rail edge 14, it being contemplated that the shoulder 20 will be moved into abutting engagement with the rail edge 14 only when the rail anchor is subjected to a retrograde movement which shifts the rail anchor diagonally of the rail to an increased inclination from that in which it is shown in Fig. 3 of the drawing. In carrying out the present invention it is contemplated 75 that the slightly resilient, laterally extending arm 17 will be held in abutting engagement with the edge 14 of the rail by the inherent resiliency of the metal forming the rail anchor, and also by the overhanging jaw 80 or jaws provided at the opposite end of the rail anchor and acting through the shank 15, to maintain the parts in the position shown in Fig. 1. As above stated it is contemplated 85 that the overhanging jaw or jaws may be variously constructed so long as they are adapted to extend inwardly a substantial distance over the rail base flange to engage the upper inclined face of this flange at a point 90 relatively near the vertical central web 12 to thereby exert a pronounced upward pressure upon the shank 15 for maintaining its upper edge 16 firmly against the rail base.

95 In the form of the invention illustrated in Figs. 1, 2 and 3, the overhanging jaws are formed by increasing the width or height of the rail anchor blank at the left-hand end portion thereof and by forming a deep undercut in this relatively wide portion of the blank to provide a clearance space adapted to receive a portion of the rail base flange, as will be apparent from Fig. 2. Through this construction the overhanging jaw 21 which is 100 disposed directly over the shank 15 is provided, and the flange engaging face 22 of this jaw is preferably inclined slightly to the face 13 of the rail base flange, as will be apparent from Fig. 2, the construction being such that when the rail anchor is forced 105 transversely of the rail into gripping engagement with the rail base flange, the inner end portion of the jaw 21 will engage the upper face 13 of the rail base, and as this jaw 21 springs upwardly slightly under a pronounced flange gripping force, the inclination of the under face of the jaw 21 will tend 110 to accommodate itself to the inclination of the upper face 13 of the rail base flange. This jaw construction insures engagement of the jaw with the inclined surface 13 at a 115 point well inwardly from an edge 14 of the rail base flange. It is desirable that the rail anchor shall clear the edge 14 of the rail so that the overhanging jaw 21 may be moved 120 transversely of the rail into firm gripping engagement with the rail base flange, and this is accomplished by cutting the rail anchor away, as indicated by 23, to form the 125 desired clearance space for the rail edge.

130 In many cases it may be desirable to pro-

vide more than one overhanging jaw to thereby increase the gripping engagement of the rail anchor with the rail base, and in the construction shown in Figs. 1, 2 and 3, a second 5 jaw 24 is provided by bending the end portion of the overhanging metal of the rail anchor back upon itself, as will be apparent from Fig. 3, to form the auxiliary jaw 24 which is connected to the first jaw 21 by the 10 arcuate portion 25, and the lower face of the jaw 24 is constructed so that it normally lies slightly below the face 22 of the jaw 21. This will cause the jaw 24 to be subjected to a torsional twist as it is forced into engagement 15 with the rail base flange. This jaw 24 will obviously be more resilient than the jaw 21 and the auxiliary jaw may therefore spring upwardly slightly to accommodate itself to the configuration of the base flange, while 20 at the same time exert a firm downward pressure upon the upper face of the rail flange. The jaw 24, it should be noted, is offset from the shank of the rail anchor away from the on-coming traffic in a direction to 25 extend over the tie 18, and as a result of this location of the jaw 24 it will oppose any tendency of the shank 15 to rock about its longitudinal upper surface 16 under the tie pressure exerted upon the face of the shank 15. 30 In the modified construction shown in Fig. 4 of the drawing the arcuate arm 17 is so constructed that its outer end portion 26 is bent inwardly to abut against the inner curved surface 27 of the arcuate arm to increase the rigidity of the entire arm and a 35 curved intermediate portion 28 of the arcuate arm abuts against the rail edge. The opposite end of the rail anchor disclosed in Fig. 4 is shown as provided with three overhanging 40 jaws; the jaws 21 and 24 of this modified construction may be formed as above described. The third jaw 29 is conveniently formed by increasing the length of the left-hand end portion of the rail anchor far 45 enough to provide the portion 30 which may be bent so that it will extend inwardly towards the central web 12 of the rail as shown, and in the edge of this inwardly bent portion 30 is formed a cut or recess as shown in 50 Fig. 7, to receive an edge portion of the rail base flange and adapted to provide the overhanging jaw 29 for engaging the rail base flange in lateral spaced relation to the jaw 21. While in some cases it may be desirable 55 to provide the rail anchor of Fig. 4 with three overhanging jaws as shown, this is not an essential feature of the present invention, and if desired either of the jaws 24 or 29 may be omitted, or if desired both of these jaws may 60 be omitted.

In the modified type of rail anchor shown in Fig. 5 the laterally extending arm 17 is produced by bending the same to form the intermediate arcuate portion having a laterally extending end portion 31 that projects away

from the rail anchor shank 15 and the inner face 32 of this arm 17 is positioned to abut against the edge 14 of the rail. The opposite end of the rail anchor of Fig. 5 is shown as provided with two jaws 21 and 29, the 70 jaw 24 of Figs. 1 to 4 inclusive being omitted.

In the modified construction shown in Fig. 6 the laterally extending arm 17 is formed substantially the same as the laterally extending arm 17 of Fig. 5, except that the arcuate portion of the arm of Fig. 6 is bent or looped to a less degree than in Fig. 5, so that the end portion 33 of the laterally extending arm of Fig. 6 is disposed further from the shank 15 than in the construction shown in Fig. 5. In this construction, as in Fig. 5, a side face 34 of the arm 17 is positioned to abut against the rail edge 14. The opposite end of the rail anchor of Fig. 6 is shown as provided with the overhanging jaws 21 and 24 which may be constructed similarly to the correspondingly numbered jaws of Figs. 1 to 4 inclusive. 80

In Figs. 1 to 5 inclusive the upstanding shoulder 20 is preferably disposed in spaced relation to the rail edge so that it is normally inactive, but as above stated may be forced into engagement with the rail edge when the rail anchor is shifted to a pronounced degree diagonally of the rail. In the modified construction shown in Fig. 6 a shoulder 35 is positioned a greater distance from the edge of the rail and is not intended to engage the edge of the rail under any condition, but is formed in cutting or shaping the laterally extending arm so that the upper portion of the arm will extend upwardly above the upper surface 16 of the shank far enough to provide a side face 34 of relatively large area which will abut against the rail edge 14. 90

In each of the embodiments shown the rail anchor may be secured to a rail base by moving the rail anchor by hand into position in which the overhanging jaw or jaws engage the upper face of the rail base, and by then striking upon the left-hand end of the rail anchor with a spike maul or the like, to force the rail anchor transversely of the rail far enough to permit the inner face of the arcuate arm 17 to spring upwardly into engagement with the opposite edge 14 of the rail under the upward pressure exerted upon the shank 15 by the overhanging jaw or jaws. In some 100 of the constructions shown, for example, the modified construction of Figs. 5 and 6, the movement of the inner face of the arcuate arm 17 into abutting engagement with the rail edge may be assisted through the use of a suitable tool which may be engaged with the arcuate arm to assist in springing it outwardly far enough to clear the under face of the rail base to permit the arm to spring upwardly into abutting engagement with the rail edge as shown. 110

It is contemplated that in each of the em- 120

130

bodiments of the invention shown, when a rail anchor is applied to a rail in service position, the laterally extending arm will exert a continuous spring pressure upon the edge of the rail to maintain the anchor in firm gripping engagement with the rail base, which will serve to prevent the rail anchor from moving lengthwise of the rail under normal or average load thrust, but when the rail anchor is subjected to a load thrust of exceptional magnitude, the edge engaging surface of the arm 17 may change position slightly relative to the rail to cause the rail anchor to increase its gripping engagement upon the rail base.

15 When it is desired to remove the rail anchor of the present invention from a rail, this is readily accomplished by striking down upon the upper face of the laterally extending arm 17 to force this arm downwardly into engagement with the under face of the rail, whereupon the rail anchor may be removed from the rail by forcing it laterally of the rail in a direction to disengage its overhanging jaws from the rail base flange.

20 What is claimed is:—

1. A one-piece rail anchor consisting of a shank adapted to extend across the rail base to abut against a tie and provided at one 25 end with an overhanging jaw adapted to extend inwardly a substantial distance over the rail base flange and engage the upper face thereof to hold the shank firmly against the under face of the rail, and an arcuate arm at 30 the opposite end of said shank extending lengthwise of the rail in the direction of the on-coming traffic and having a side face adapted to be sprung into abutting engagement with the rail edge and disposed in its 35 entirety at one side of the shank.

40 2. A one-piece rail anchor consisting of a shank adapted to extend across the rail base and provided at one end with an overhanging jaw adapted to engage the upper inclined face 45 of the base flange at a substantial distance from the edge thereof to hold the shank firmly against the under face of the rail, and an arcuate arm at the other end of the shank extending lengthwise of the rail in the direction 50 of the on-coming traffic and having a side face disposed in its entirety at one side of the shank and adapted to abut against the edge 55 of the rail and to be held thereagainst and from moving downwardly out of engagement with said edge by said jaw acting through the shank.

60 3. A one-piece rail anchor consisting of a shank adapted to extend across the rail base to abut against a tie and provided at one end with an overhanging jaw adapted to extend 65 inwardly a substantial distance over the rail base flange and engage the upper face thereof to hold the shank firmly against the under face of the rail, and a laterally bent arm at the opposite end of said shank extending

therefrom in the direction of the on-coming traffic and having a side face disposed in its entirety at one side of the shank and adapted to abut against the edge of the rail base flange at a point sufficiently offset from the shank to shift the latter diagonally of the rail slightly and arranged to be held against the edge of the rail by the jaw and shank.

70 4. A rail anchor consisting of a shank adapted to extend across the rail base and provided at one end with an overhanging jaw adapted to engage the upper inclined face of the base flange at a substantial distance from the edge thereof to hold the shank firmly against the under face of the rail, and a loop-shaped arm at the other end of the shank extending lengthwise of the rail and formed so that its outer side face is bent to abut against the edge of the rail base flange and is held thereagainst by the jaw and shank.

75 5. A rail anchor consisting of a shank adapted to extend across the rail base and provided at one end with an overhanging jaw adapted to engage the upper inclined face of the base flange at a substantial distance from the edge thereof to hold the shank firmly against the under face of the rail, and an arm extending from the opposite end of the shank in the direction of the on-coming traffic and having an arcuate portion and a straight portion arranged so that a side face of the latter disposed in its entirety at one side of the shank abuts against the edge of the rail and is held thereagainst by the jaw and arm.

80 6. A one-piece rail anchor consisting of a shank adapted to extend across the rail base to abut against a tie and provided at one end with an overhanging jaw adapted to extend 85 inwardly a substantial distance over the rail base flange and engage the upper face thereof to hold the shank with its upper edge firmly against the under face of the rail, and an arm at the opposite end of the shank extending therefrom lengthwise of the rail and having a reversely bent portion the outer side face 90 of which abuts against the edge of the rail flange base and is held thereagainst by the jaw and shank.

95 In testimony whereof, I have signed my name to this specification.

CHARLES G. ERICSON.
